DESIGN FOR A REFLECTOR FOR ARTIFICIAL ILLUMINATION

Emanuel C. Smally, Canton, Ohio

Application October 25, 1940, Serial No. 96,084

Term of patent 3½ years

To all whom it may concern:

Be it known that I, Emanuel C. Smally, a citizen of the United States, residing at Canton, in the county of Stark and State of Ohio, have invented a new, original, and ornamental Design for a Reflector for Artificial Illumination, of which the following is a specification, reference being had to the accompanying drawing, forming a part thereof, in which the single figure is an isometric view of a reflector for artificial illumination showing my new design.

The triangular end surface not seen in the drawing is the same as the end seen, and the rectangular surface not seen in the drawing is plain.

I claim:

The ornamental design for a reflector for artificial illumination, as shown and described.

EMANUEL C. SMALLY.
